CLAIM

The ornamental design for a photograph display stand, as shown and described.

DESCRIPTION

FIG. 1 is a right side elevational view of a photograph display stand showing my new design;

FIG. 2 is a right side elevational view thereof;

FIG. 3 is a top plan view thereof;

FIG. 4 is a bottom plan view thereof; and

FIG. 5 is a right side elevational view similar to FIG. 2 showing the photograph display stand in a transitory position.

The left side elevational view is substantially a mirror image of the right side elevational views shown in FIGS. 2 and 5.
